UNITED STATES PATENT OFFICE.

ALFRED E. ANDERSON AND CHARLES A. FORSBERG, OF ROCKFORD, ILLINOIS.

SOFA BED.

Application filed February 17, 1923. Serial No. 619,866.

This application is a continuation in part of Serial No. 255,387, filed Sept. 23, 1918, allowed February 13, 1923.

This invention relates to household furniture generally known as sofa beds adapted to be quickly converted from a sofa into a bed, and vice versa, and has more particular reference to that type of sofa bed having a pivoted seat connected with a sectional bed bottom for assisting in moving the latter to a concealed inoperative position within the sofa frame and to an extended flat position overlying the seat by respectively moving the seat to and from an operative position.

The primary object of the present invention is to provide a generally simplified and improved sofa bed of this type, which shall be easily convertible from one position to another and which shall be so constructed that it may be produced at a comparatively low cost and will serve effectually and satisfactorily the purposes for which it is designed.

In furtherance of these general objects, we have provided a novel means for supporting the sectional bed bottom and for guiding it to and from its several positions; and in this regard, special attention is called to the particular form and arrangement of the guides for guiding the head section of the bed bottom vertically when the bed bottom is either being collapsed or straightened out, and also for automatically locking the bed bottom in its flat or operative position. In the present embodiment of our improvements, these rear guides are preferably in the form of vertical rods fixed to the frame sides and guides pivoted on the head section of the bed bottom and slidably embracing the rods. A simple but very effectual lock is provided by forming an offset in the lower end of each rod, which offset guide will engage to hold the bed bottom in flat position upon its being moved thereto. This construction and its attendant advantages will be described more fully hereinafter.

Still another object resides in the provision of foot rests attached to the seat frame for supporting its extended end in inverted position and having upward extensions which receive the overlying bed bottom and serve to support the same in operative position.

Other objects and attendant advantages will be appreciated as the invention becomes understood by reference to the following description when considered in connection with the accompanying drawings, in which—

Fig. 1 is a plan view of a sofa bed embodying our improvements, showing the bed bottom in its extended operative position and with the back rest removed for the purpose of clarity; Fig. 2 is a longitudinal vertical sectional view through the sofa bed taken substantially on the line 2—2 of Fig. 1; Figs. 2^a and 2^b show shapes of the supporting ends of the legs; Fig. 3 is a fragmentary detail rear view of one of the guides and guide rods for the head section of the bed bottom; Fig. 4 is a sectional view similar to Fig. 2 but showing the bed bottom in the course of being moved to its inoperative position; and Fig. 5, a similar sectional view showing the sofa bed in the form of a sofa.

The frame of our improved sofa bed is so designed that it may be compactly arranged in knocked down condition for shipment and set up quickly and easily by the dealer without the use of special tools. The frame consists preferably of a rectangular box designated generally by character 6 having front and back pieces 7 and 8 respectively, joined together by sides 9. To the sides 9 of this box-like frame are detachably secured by suitable means, such as bolts and wing nuts 11, sides 12, which may be of any suitable or preferred design. Pivotally attached to the front board 7 of this frame construction is a seat 13 which also may be of any suitable construction, it being preferred that the seat shall include a rectangular frame having sides 14 suitable for the attachment of links or levers which will be mentioned hereinafter as forming part of the bed bottom supporting means. When the seat is in the operative position shown in Fig. 5, its sides 14 rest on the sides 9 of the main frame structure, and when swung forward about its pivot to the inverted position shown in Figs. 2 and 4, it is supported at its extended end by legs 15, which in the present instance, are in the form of angle iron bars fixedly secured to the back of the seat frame. These angle iron bars are extended above the seat (considering the latter in inverted position) and provide rests 20 which serve to support the bed bottom in operative position as will be presently mentioned. The upper ends of the rests 20 have a supporting shoulder 20' a short distance below and at an angle to the extremity 20' which may sharply abut the end portion as shown in Fig. 2^a or be connected thereto by an inclined portion 20^b shown in Fig. 2^b.

The bed bottom designated generally by

character 16 is of sectional construction consisting preferably of a head section 17 pivotally connected at 18 to a medial section 19 and a foot section 21 pivotally connected at 22 to the medial section 19. A suitable foot rail 23 is also employed. This sectional frame supports a wire spring or spring mattress 24, it being understood that the shape, proportions and materials from which the bed bottom is made might be varied to suit the size and type of bed being made. In the present instance, a comparatively heavy brace rod 25 is pivotally connected to and interposed between the forward ends of the head section 17 of the bed bottom for preventing the medial portion of the bed bottom from buckling inwardly during usage.

Novel means are now provided for so supporting the bed bottom that it may be very quickly and easily moved from a concealed position within the sofa bed to an extended operative position. Such means consist of links or levers 26 pivotally connected at 27 to the sides 9 of the main box frame and pivotally connected at 28 to the head section 17 of the bed bottom about medially of the ends thereof. Forward links or levers 29 are pivotally connected at 31 and 32 to the sides 14 of the seat frame and to the section 19 of the bed bottom respectively, as shown. During the operation of moving the bed bottom to and from its different positions, the links 29 will be swung forwardly and backwardly upon and with respect to the sides 14, and for the purpose of holding these links against lateral displacement and for limiting their forward and backward movement to attain certain results, strap iron guides 33 are attached to the inner sides of the seat sides 14 and provide a guideway defined at its ends by stops 34 and 35. When the bed bottom is in the flat operative position shown in Fig. 2, the links 29 rest against the stops 34, thus preventing further lowering movement of the bed bottom. It will also be observed that the forward end of the bed bottom is also seated on the upward extensions 20 of the legs 15 and thus held against lateral displacement and supported in operative position in a very substantial manner. With the extremity shown by Fig. 2^a there is a little side play if the bed bottom fits loosely therein, but with the inclined portions 20^b, as shown in Fig. 2^b, the bed bottom is wedged therebetween, thus binding the legs and bed bottom more firmly together and supporting the latter more rigidly upon the floor.

Means is now provided for guiding the head end of the head section so that it will travel in a vertical path when the bed bottom is moved to and from its several positions. This means consists of a vertical guide rod 36 rigidly mounted at each side of the sofa bed. In the present instance, these guide rods are inserted at their upper ends in holes

in the head bar 30 rigidly joining the top of the sides 12 and are fixedly secured at their lower ends to brackets 37 attached to the sides 12. The head section 17 is slidably guided on the rods 36 through the intermediary of guide parts 38 which embrace the rods 36 and are pivotally connected at 39 to the bed bottom section so as to be capable of oscillating freely about a horizontal pivot. The parts 36 and 38 in addition to serving as guides are also designed to automatically lock the bed bottom in its operative position when the bed bottom is moved thereto. For this purpose the lower end of the rods 36 are offset slightly as at 41, so that when the guides 38 reach their lowermost position they will engage behind the shoulders of the offsets 41 and be prevented from sliding upwardly. This is due to the fact that the weight on the bed bottom at its head end is carried by the parts 38 resting on the brackets 37 and by the links 26, and that any tendency for the medial portion of the bed bottom to buckle downwardly and consequently allow the rear end of the bed bottom to slide upwardly, will be precluded by reason of the lock effected by the offset in the guide rods 36. The bed bottom is also held in alignment by the bed fabric 24, and its usual marginal springs, which are drawn taut when the foot section is pulled manually outwardly and pressed down, in opening the bed. This locking effect is, however, immediately broken when the foot sections 21 and 19 of the bed bottom are successively swung upwardly and toward the main frame when commencing to return the bed bottom to its inoperative position. This initial movement of the foot and medial sections of the bed bottom in swinging them backwardly upon the links 29 will, it is obvious, move the section 17 rearwardly and upwardly, thus breaking the locking effect just mentioned, and allowing the guides 38 to slide freely upon the guide rods 36.

In moving the parts from the bed position shown in Fig. 2, to the sofa position shown in Fig. 5, the foot section 21 is swung upwardly and thence the forward end of the section 19 is raised from the rests 20 and at the same time pushed rearwardly so that the bed bottom swings on the links 29 about the pivots 31 to the position shown in Fig. 4, in which further movement in this manner is limited by contact of the links 29 against the stops 35. In the meantime, the guides 38 have been automatically released from the locked position mentioned above and the head end of the head section 17 has been guided upwardly by said guides to the elevated position shown in Fig. 4, the links serving during this movement to support and maintain the proper relative relation of the sections 17 and 19. The extended end of the seat 13 is now lifted and swung in a clockwise direction

about its pivot to the operative position shown in Fig. 5. By this action, movement will be imparted to the bed bottom through the agency of the links 29 in such manner as to carry the bed bottom to the position shown in Fig. 5 in which the section 17 stands vertically and the section 19 assumes a horizontal position, allowing ample room for the mattress and bedding at the rear of and beneath the seat. From the foregoing it will be noted that the bed bottom in being moved to and from its several positions is carried entirely by swinging links and the only sliding engagement is that of the guides 38 on the vertical slide rods 36. As a consequence of this construction, the operation of moving the bed bottom to and from its several positions may be performed very quickly and with very little effort as distinguished from some forms of sofa beds having long trackways and guides which impose considerable frictional resistance to the movement of the bed bottom and are quite difficult to operate.

The back rest 42 instead of being mounted to swing upwardly on one or more pivots as is the common practice, is designed to have a vertical sliding movement and to be automatically locked in elevated position upon being moved thereto. To this end, we have equipped the back rest with a pair of vertical slide rods 43 having an inclined portion 44 at their upper ends and a lateral offset or bend 45 at their lower ends. These rods are fixed to the back of the back rest at each end thereof and each passed through an aperture in a guide plate 46 secured to the adjacent side 12 of the sofa bed. When in normal position, shown in Fig. 5, the back rests on the seat and against the legs 15 and the top edge of the back overlies the finishing strip 47 at the under side of the head bar 30. When it is desired to raise the back rest, the operator grasps the under edge of the rest with one hand at each end thereof and pushes the back upwardly. During the initial upward movement the inclined portions 44 of the slides 43 will cause the upper end of the back to move forwardly so as to clear the head bar 30, whereupon the back may be freely raised to its elevated position. Upon reaching this position, the offset portions or bends 45 will enter the guides 46, and since the weight of the back rest is thrown rearwardly of these bends 45 the latter will engage in the apertures in the stationary guides and hold the back rest in elevated position, shown in Fig. 2. To lower the back rest it will be necessary to swing its upper end forwardly, allowing its offset portion to pass through the apertures in the stationary guides and also allowing the slide rods 43 to pass downwardly to the operative position shown in Fig. 5.

It is believed that the foregoing conveys a clear understanding of our improvements and the objects prefaced above, and it should

be understood that while we have illustrated and described but one working embodiment of our improvement, various changes might be made in the construction and arrangement without departing from the spirit and scope of the invention as expressed in the appended claims:

We claim:

1. In a sofa bed, the combination with a main frame, of an invertible seat hinged therein, legs secured to the seat and having portions projecting above it when it is inverted, and a bed bottom foldable in the frame and comprising sections one of which is supported by and engaged between but not attached to the projecting portions of said legs.

2. In a sofa bed, the combination with a main frame, of a seat invertible at the front thereof, supports projecting upwardly from the seat when it is inverted, and a bed bottom foldable in the frame and comprising pivotally connected parts unattached to the supports but adapted to rest upon and engaged between the supports for holding the bed bottom in an alined position above the seat.

3. In a sofa bed, the combination with a main frame, of a seat invertible at the front thereof, legs secured to the outer side of the seat and having portions projecting above the seat when it is inverted, the bed bottom foldable in the frame and comprising means for connecting one of the bed bottom sections with the underside of the seat, the upper ends of the legs when the seat is inverted being unattached to but adapted to engage the edges of the bed bottom holding it therebetween for steadyng it with respect to the seat.

4. In a sofa bed, the combination with a main frame, of a seat hinged to swing outwardly therefrom, a foldable bed bottom having links connecting it to the frame and to the seat for unfolding the bed bottom when the seat is inverted, and means extending upward from the underside of the seat when it is inverted and unattached to but for engaging the outer edges of the sides of the bed bottom parts for confining the bed bottom therebetween and limiting the relative lateral movement of the bed bottom and the seat.

5. In a sofa bed, a main frame and a seat invertible in front thereof, a foldable bed bottom, legs attached to the outer edge of the seat for supporting it when inverted and having extensions above the seat in this position, the bed bottom edges engaging the extensions and also being supported thereby, but not being connected thereto, the engaged parts mutually steadyng each other.

6. In a sofa bed, a main frame, a seat invertible at the front thereof, a bed bottom having foldable parts, legs fixed at the outer side of the seat when inverted, the legs having extensions above and below the seat, the lower ends resting upon the floor and the upper ends

engaging the bed bottom parts below and at the side edges of said parts for supporting and steadyng the bed bottom.

7. In a sofa bed, a main frame, a seat invertible at the front thereof, a bed bottom having foldable parts, legs fixed at the outer side of the seat when inverted, the legs having free extensions above the seat, for engaging some of the parts and confining the bed bottom therebetween to steady it.

8. In a sofa bed, the combination of a sofa frame having a back and a seat hinged to the front of the frame and movable on its hinge to an inverted position in front of the frame, a bed bottom including pivotally connected sections, the rear section occupying an upright position at the back of the frame and the other section occupying a substantially horizontal position within the bottom of the frame in the folded condition of the bed bottom, a link disposed below the bed bottom in its operative position and pivoted to the sofa frame and to the rear bed section intermediate the ends thereof, the pivotal connection between the link and the bed section constituting a swinging fulcrum on which the bed section turns in moving from its operative position to its folded position, another link disposed below the bed bottom in its operative position and pivotally connected to the seat and to the other bed section, and means for guiding the rear end of the rear bed section in an upright direction from its operative position to its folded position, said guiding means including a pair of upright rods having corresponding offsets at the lower ends, and slides carried by the rear bed section and working upon the respective guide rods, the offset portions of the guide rods overhanging the slides in the operative position of the bed bottom.

9. In a sofa bed, the combination of a sofa frame having a back and a seat hinged to the front of the frame and movable on its hinge to an inverted position in front of the frame, a bed bottom including pivotally connected sections, the rear section occupying an upright position at the back of the frame and the other section occupying a substantially horizontal position within the bottom of the frame in the folded condition of the frame in the folded condition of the bed bottom, a link disposed below the bed bottom in its operative position and pivoted to the sofa frame and to the rear bed section intermediate the ends thereof, the pivotal connection between the link and the bed section constituting a swinging fulcrum on which the bed section turns in moving from its operative position to its folded position, another link disposed below the bed bottom in its operative position and pivotally connected to the seat and to the other bed section, means for guiding the rear end of the rear bed section in an upright direction from its operative position to its folded position,

tion, and stops carried by the seat and disposed at opposite sides of the last mentioned link for limiting the swinging movement thereof.

10. In a sofa bed, the combination of a frame, a seat pivoted thereon and adapted to be swung forward to an inverted position, a bed bottom having pivotally connected sections, links pivotally mounted on the frame and seat for supporting said sections respectively of the bed bottom and upon which the bed bottom will swing when being moved to and from operative position, stops on the seat for limiting the rear and forward movement of the said links when moving the bed bottom to operative and inoperative positions respectively, and means for guiding the rear end of the bed bottom vertically at the rear portion of the frame when the bed bottom is swung on said links to inoperative position.

11. In a sofa bed, the combination of a main frame, an invertible seat hinged thereto, a sectional bed bottom, vertical guides for the rear end of one of the sections, supporting means at the bottom of said guides, two pairs of pivoted swinging links, one pair connected at the sides of the frame to one of the bed sections and the other pair connected intermediate the ends of the adjacent bed section and the underside of the seat, and supporting legs at the rear of the seat for supporting it in an inverted position and extending above the seat when in this position, the pairs of links guiding the movement of the bed sections from behind and below the seat to a horizontal position above the seat when the latter is inverted and sliding the rear of the first named section downwardly against the supports at the bottom of the guides and swinging the outer end of the said adjacent section to engage between the upper ends of the supporting legs.

12. In a sofa bed, the combination of a main frame, an invertible seat hinged thereto, a sectional bed bottom, vertical guides for the rear end of one of the sections, supporting means at the lower ends of the guides, swinging links connected to the side of the frame and intermediate the ends of one of the sections, other swinging links connected to the underside of the seat and intermediate the ends of the adjacent section, legs at the rear of the seat extending above and below it for supporting the seat in inverted position, the bed sections being movable from behind and below the seat to an alined position above the seat when it is inverted and vice versa, and the outer movement of the seat causing the rear bed section to slide downwardly on the guides and the links guiding the said adjacent section to swing downwardly into engagement with the upper ends of the supporting legs, and means at the lower ends of the guides to prevent accidental upward movement of the rear bed bottom section.

13. In a sofa bed, the combination of a main frame, an invertible seat hinged thereto, a sectional bed bottom, vertical guides for the rear end of one of the sections, supporting means at the lower ends of the guides, swinging links connected to the side of the frame and intermediate the ends of one of the sections, other swinging links connected to the underside of the seat and intermediate 5 the ends of the adjacent section, and legs at the rear of the seat extending above and below it for supporting the seat in inverted position, the bed sections being movable from behind and below the seat to an alined position 10 above the seat when it is inverted and vice versa, and the outer movement of the seat and links causing the rear bed section to slide downwardly on the guides and move into engagement with the supporting means 15 and the links guiding the adjacent section to swing downwardly into engagement with the upper ends of the supporting legs.

14. In a sofa bed, the combination of a frame, an invertible seat pivoted therein, a 20 sectional bed bottom, means for slidably guiding the rear of the rear bed bottom section from and to a position above and behind the seat in a substantially vertical path and swinging the front forwardly and rearwardly, links pivotally connecting the next bed 25 section intermediate the ends of its sides with

the underside of the seat whereby these sections assume an intermediate balanced and inclined substantially right angled position when the seat is inverted, and presenting in 35 this position a hand graspable portion by means of which the sections are drawn outwardly into horizontal alinement.

15. In a sofa bed, a frame, a pivoted bed bottom of three different sized sections, a vertical guide for the rear of the widest section, a link at each end of the frame pivoted to the end of this section, a seat hinged at the front of the frame, a support for the outer side of the seat when overturned extending also 40 above the seat in this position, links pivoted to the underside of the seat and to each end of the next adjacent bed section, stops in the seat for limiting the movement of the seat 45 links, the outermost bed section being shortest and forming with the other bed section a J-shaped bed clothes receptacle which is maintained in this same position by the said links in an intermediate position when the seat is overturned, the seat support engaging 50 the outer edges of the second bed section in bed position, and the shortest bed section extending beyond the seat support and being upheld by the second bed section.

ALFRED E. ANDERSON.
CHARLES A. FORSBERG.
